UNITED STATES PATENT OFFICE

CHARLES J. HUBER, OF BALTIMORE, MARYLAND, ASSIGNOR OF ONE-HALF TO FLYNN
AND EMRICH COMPANY, OF BALTIMORE, MARYLAND, A CORPORATION OF MARY-
LAND

FURNACE

Application filed August 25, 1927. Serial No. 215,230.

The invention relates particularly to a furnace in which the coal is fed to the forward end of the grate and moved backwardly as combustion progresses. The motion may be the result of the rocking of the grate bars at intervals either manually or mechanically. In the form of stoking grate illustrated the grate is inclined and the downward and rearward inclination assists in this operation. A stoker of this type is fully described in my reissue Patent No. 15,124.

In the preferred type of furnace to which the invention as illustrated in the drawings is applied, the fuel is fed automatically from a hopper and there is a coking shelf beneath the hopper extending backwardly into the furnace at the bottom of the hopper opening, and above the grate. There is also an air opening beneath the coking shelf and forward of the rear edge of the same and in the preferred form of the furnace front, as illustrated, there is an arch of resistive material above the coking shelf inclined upwardly and rearwardly and extending backward into the furnace. The coking shelf and the arch are exposed to the direct radiation from the fire and become highly heated. The fuel as admitted piles up on the coking shelf where it is subjected to a very high temperature and is partially or fully coked before being fed to the grate, the feeding being ordinarily accomplished by a pusher which operates beneath the hopper. The air which enters beneath and forward of the coking shelf passes upwardly in contact with the green coal on the shelf and in contact with the highly heated arch, mingling with the gases from the coke and burning them.

In accordance with the operation of the apparatus as illustrated in Patent No. 1,666,418 the wholly or partially coked fuel is dropped from the rear edge of the coking shelf on to the forward end of the grate, which, as shown, in the patent is preferably inclined downwardly to the rear. From the forward end of the grate the coked fuel is fed backward, as already outlined, by the intermittent rocking of the stoker bars.

Under the circumstances thus outlined, the fuel as it is piled up on and about the for-

ward end of the grate tends to roll or flow forwardly obstructing the air passage, part of it falling into the ash pit where it is mingled with the refuse, ashes, clinker, etc., and being discarded therewith is wasted. Also 55 the fuel thus dropped forward of the rear edge of the coking shelf is subjected to an excess of cold air and sheltered by the fuel directly in front of it from the heat of the furnace and is not burned most efficiently 60 at this point and part of it is dropped into the ash pit, as aforesaid, before it can be fed forward into the more efficient combustion area. It may be added that an opening through the fire door to the fire for inspection, 65 for hand stoking and for the admission of tools for removal of clinkers and to clear the grate, has always been regarded as necessary and is further retained in the present structure. 70

The invention relates to the provision of an upright grate at the rear edge of the coking shelf whereby the tendency of the fuel to flow forwardly and close the air opening is prevented. The new upright grate or grating 75 admits air freely from the opening beneath the coking shelf and permits it to pass upward over the surface of the coking shelf, the fuel as fed being deflected to the rear onto the hotter and more efficient combustion 80 area of the grate. This vertical grate is also arranged in sections which may be rotated downwardly to give access to the fire and grate area from the fire door without releasing or losing the fuel which is resting on the 85 section of the grate being moved.

In the accompanying drawings I have illustrated an upright grate or grating applied to the front of a stoker grate and so much of a furnace front and rocking bar stoker as is regarded as desirable to show the application and operation of the same. 90

In the drawings:

Figure 1 is a vertical fore and aft central section through a unit of a furnace and stoker equipped in accordance with the invention, the same being taken on the line 1-1 in Figure 2. 95

Figure 2 is a section on the line 2-2 of Figure 1. 100

Figure 3 is an elevation on a somewhat enlarged scale of the upright grates, certain parts being sectioned on the line 3-3 in Figure 1. The observer is looking to the right in Figure 1 or toward the rear.

Figure 4 is a section on the line 4-4 of Figure 3 looking to the left in that figure.

Figure 5 is a section on the line 5-5 of Figure 3.

Referring to the drawings by numerals, each of which is used to indicate the same or similar parts in the different figures, the furnace structure, as illustrated, includes a furnace front 1 having a coking shelf 2 spaced above which is the arch 3 inclined upwardly to the rear, as shown, and between the arch and the coking shelf is the feed opening 4 through which the fuel is fed, in the form of the invention shown, from and by means of hopper 5 which may be equipped with a pusher 6 of any well known type. The fire door 7 closes a hand stoking opening or passage 8 which enters the furnace beneath the coking shelf and at the top of the grate 9. The grate 9 is preferably of the stoking type. As shown, it is composed of rocking bars 10, as in my reissue patent referred to above, which may be actuated by hand lever 11 through rod 12, or in any suitable manner, the bars being pivoted at 14 and supported on side bars 15.

The two forward grate bars previously used are omitted, the notch 17 spaced well backwardly from the forward ends of the side bars 15 and substantially beneath the rear edge of the coking shelf being occupied by the trunnion 18 of the upright grating or grate 19, to be described. The omission of the forward grate sections provides a free and unobstructed air opening 20 at this point of extended area, in addition to the opening 21 forward of the grate. The fuel is excluded from this opening by the upright grate or grating 19.

The arch 3 may also be provided with an air opening 22, 24, which discharges just inside the feed opening 4 at the top thereof, being mixed with the gases from the coking fuel 25 on the shelf as they pass over the surface of the heated arch 3, igniting the fuel on the shelf and tending to complete combustion produced by the intermingling of these combustible gases with the air which enters at the front of the grate, as already described, and passes with the combustible gases in contact with the heated members 2 and 3.

The invention relates particularly to the provision of the upright fuel support and grate member 19, separately, and in combination with other features. This member 19 consists of a wall or support which is preferably upright or slightly inclined from the upright and slotted or perforated at 27. The upright support or grate 19, as shown, comprises a stationary portion 28 connected by

frame member 29 which may be mounted on trunnions 18 projecting therefrom near the bottom at each side and fitting in the notches 17 in the side bars. These upright supporting walls or grids are provided one for each grate section 30, 31 and 32, as shown in Figure 2, the trunnions 18 being, for this purpose, of a length slightly less than one-half the width of the side bars at the notches 17 so that the trunnions can be placed end to end, the upright grids or supports being formed in sections 33 of the width of each grate section. The stationary portion 28 of each section is made in an upright "U" shape as seen from the front in Figure 3, i. e., each section is provided with a central door opening 34 closed by means of a swinging grid 35. Each said swinging grid is provided at the bottom with forwardly disposed journal notches 36, it being understood that Figure 3 is a view looking at the grid or supporting wall from the front, i. e., from the left in Figure 1. The notches 36 enclose trunnions 37 projecting inwardly from the stationary portions 28 of the grid into the opening 34 near the bottom so that when the grids 35 are hung on the trunnions by means of the notches they close the openings 34. The stationary members 28 are provided on each side with forwardly projecting wings 38 and 40 which may to advantage be perforated at 39 for the convenient admission of air. The wings 40 rest on side bars 15 to support the upright grate structure.

The swinging grids 35, as shown, may be conveniently controlled by a toggle including an arm 41 pivotally connected at its upper end to the swinging grid 35 at 42 as by means of ears 43, Figure 3, and at the other end at 44 to the upright arm 45 of a bell crank lever 46 which is pivotally mounted at 47 on a bracket 48. The other arm 49 of the bell crank projects forwardly and is provided with a handle 50.

In the closed position of the swinging grid 35 the pin 44 connecting the links 41 and 45 swings rearwardly beyond the line connecting the opposite ends of these levers, i. e., a straight line drawn from 42 to 47 giving a toggle action and locking the grid in closed position. When the handle 50 is engaged and swung downwardly the swinging grid 35 is released and in turn swung downwardly about its trunnion 37, but the grid moves between the wings 38 so that while opening of the grid affords access to the fire through the fire door 7 and a view of the inside of the furnace, the fuel supported by the grid in its closed position is not released but is retained between the grid and the wings 38. This makes it feasible to open the upright grid at any time to give access to the fire for any purpose without releasing the fuel. The upright grid or grate provides a convenient support for the fuel giving an air opening 130

at the front of large area which is not closed by the fuel as fed, as the upright support holds it back of the coking shelf and in the heated combustion area. The air thus enters 5 freely from the ash pit forwardly of the grid between the side bars 15 and passes beneath the coking shelf and through the perforations or slots 27 in the upright wall or grid which slots are never more than partially 10 obstructed by the accumulated fuel. In this way the air comes into contact with the newly ignited fuel falling from the coking shelf and is closely mingled with the gases in the most highly heated area, supplying an 15 excess of oxygen to be mingled with these gases and to pass upwardly in contact with the fuel which is falling from the coking shelf, or about to fall therefrom.

I have thus described specifically and in 20 detail a furnace structure and grate embodying the features of my invention in the preferred form in order that the nature and operation of the same may be clearly understood, however, the specific terms herein are 25 used descriptively rather than in a limiting sense, the scope of the invention being defined in the claim.

What I claim as new and desire to secure by Letters Patent is:

30 In a furnace, the combination with a coking shelf and a grate beneath the coking shelf, of means in the form of an upright grid section extending upwardly from the grate at a sharp angle to the grate substantially to 35 the coking shelf, the upright grid section comprising a stationary portion and a swinging section which may be rotated forwardly and downwardly to give access to the fire, a fire door aligned with said swinging section, 40 the upright grid section having at each side of the swinging member a forwardly projecting wing immediately adjacent and parallel to the path of said swinging section to support the fire when the swinging section is 45 moved downwardly.

Signed by me at Baltimore, Maryland, this 22nd day of August, 1927.

CHARLES J. HUBER.
